HEMOGLOBINOMETER

Erwin Fritzsching, Nepera Park, N. Y., assignor
to Rare Chemicals, Inc., Nepera Park, N. Y., a
corporation of New York

Application May 23, 1935, Serial No. 23,123

5 Claims. (Cl. 88—14)

My present invention relates to hemoglobinometers for use in determining the percentage of hemoglobin in the blood.

The principal general object of my present invention is to provide hemoglobinometers characterized by simplicity of construction especially adapting them for use as permanent records, each one being relatively thin and somewhat the same as index cards, so that they may be conveniently filed.

The more specific objects of the invention include the provision of hemoglobinometers constructed of foldable material, such as paper or cardboard, divided by creases into a plurality of panels foldable one over the other, and having incorporated therein a rotatable disk carrying areas of colors of predetermined character with openings therethru to facilitate comparison with a sample of blood on a piece of paper inserted in the folder, as hereinafter pointed out.

Another object of the invention is to provide a hemoglobinometer in the nature of a flat folder, having on one flap a record chart for the name, age, weight, and other characteristics of the patient, as well as the results of previous tests, with the chart so arranged as to afford ready reference thereto while making an actual test.

The foregoing and other objects and advantages of the invention will become apparent and will be pointed out during the course of the following detailed description of the accompanying drawing, in which—

Fig. 1 is a plan view of a blank or sheet from which a preferred form of my hemoglobinometer is constructed;

Fig. 2 is a sectional view taken on the line 2—2 of Fig. 1;

Fig. 3 is a fragmentary view showing the sheet of Fig. 1 partly folded, or in the process of assembly;

Fig. 4 is a perspective view of a complete hemoglobinometer constructed from the blank of Fig. 1, with a piece of paper having thereon the representation of the sample of blood in position to be inserted;

Fig. 5 is a sectional view taken on the line 5—5 of Fig. 3;

Fig. 6 is an end elevation of the complete device of Fig. 4, when in closed position, and showing in dot-and-dash lines the cover or panel bearing the record chart in open position; and

Fig. 7 is a plan view of a fragment of a sheet of paper sub-divided to provide slips to receive the blood samples.

55 Referring to Fig. 1, the letters A, B, C, and D

designate, respectively, the panels of a sheet or blank from which the hemoglobinometer is constructed, and connected respectively along creases 8, 9 and 10.

As shown most clearly in Figs. 1, 2, 3 and 5, 5 the panel A is provided with arcuate slits which permit wings or tabs 11 to be bent up from the panel so that a disk 12 may be secured to the panel A for rotation with respect thereto by inserting the tabs 11 through the circular opening 10 10 in the disk and then bending the tabs down against the front face of the disk.

The disk is shown provided with a plurality of 15 circular areas 14 in different tones or shades of red scientifically determined to correspond to different colors according to the hemoglobin content of blood. The panel A is preferably not as wide as the panels B and C, and the disk 12 is so arranged on panel A and of such size that an arc of the outer edge of the disk projects beyond 20 the edge 15 of the panel A. This last feature is provided so that when the panel A is folded along the crease 8 down against the panel B the projecting edge of the disk will extend across an elongated opening 16 located between panels B and C 25 and along the crease 9, as shown in Fig. 3.

The panel A is provided in its top edge with an 30 elongated slot 17 extending down behind a portion of the disk 12 and past which the areas 14 move as the disk is rotated. Similarly the panel B is provided with a slot 18 in its upper edge adapted to register with the slot 17 when the panel A is folded over on panel B, as in the position of Fig. 3. Beneath the slot 18 in the panel B is a sight opening 19, past which the areas 14 35 must also move as the disk is rotated. I have shown opening 19 of substantially key-hole-shape so that the lower portion thereof will expose the indicating numerals or indicia adjacent each of the areas 14 as the areas are moved past the 40 opening 19, as shown in Fig. 4.

The panel C is preferably provided with indicating indicia "Insert filter paper here", as indicated generally by the numeral 20, at its top approximate center, aligned with the notches 17 and 45 18 when the blank is folded to the position of Fig. 4. The lower edge of panel B is notched at 21.

The inner face of the panel D is preferably provided with a chart to contain the name of the 50 patient or person whose blood is to be tested, and spaces in which there may be recorded the results of the different tests from time to time for reference in determining the progress of the case. The blank D also has at its outer edge a tab 22 55

on which may be written or recorded identification of the case so that the hemoglobinometer may be readily selected from a file box, drawer or case by reference to the data on the tab 22. 5 This tab projects beyond the opposite side of the folded or assembled hemoglobinometer as shown in Fig. 6.

In forming the hemoglobinometer, the openings 16, 18, 19, 20 and 17 and the slits which form the tabs 11, may be simultaneously formed by any suitable implement, as also may be the creases 8, 9 and 10. When the disk 12 has been rotatably secured to the panel A, as shown and above described, to complete formation of the hemoglobinometer, the panel A is folded over on crease 8 to bring the slots 17 and 18 into registry and to place the face of the disk 12 against the inner surface of panel B, so that the areas 14 will be so positioned as to pass the opening 19. The panel 20 C (or the back of panel A) may be spotted with adhesive, as indicated at 23, to hold the panels A, B and C in the form of an open ended envelope with the slots 17 and 18 in registry with the indicia 12. This provides a pocket into which the strips of paper containing the samples of blood may be inserted between disk 12 and panel C, and between the edges of the slot 17. In Fig. 4, I have indicated the slip of paper by the numeral 24 having thereon a spot of blood 25. Obviously, 30 when this piece of paper, which is preferably narrower than slot 17, is inserted into the slot and between the disk 12 and panel C, it will be prevented from rotating when the disc 12 is rotated. Furthermore, the depth of the slot 17 with respect to the size of the slip 24, is preferably such that the area covered by the blood adjacent one end of the slip will register with openings 26 in the areas 14 of the disk 12. Thus the areas 14 are directly over the spot of blood and the spot of 40 blood may be observed thru openings 26 in direct comparison with the areas 14.

As will be noted, in Figs. 3 and 4 an edge of the disk 12, when the panels are folded one on the other, extends thru the slot 16 so that the exposed edge of the disk, which is preferably roughened or scalloped, may be engaged by the finger to rotate the disk.

As should also be obvious, the cutaway portion 21 of panel B, as best shown in Fig. 4, provides for 50 access to the supply of paper containing the strips 24, which may be housed or kept in the pocket between panels B and A beneath disk 12. The supply of paper is shown in Fig. 7, as comprising a sheet designated generally by the numeral 27, having scored lines 28 marking off or dividing the slips 24 which may be removed from the sheet of paper by tearing along the lines 28. The reserve supply or sheet 27 is folded into compact form so that it will fit within the pocket between the 60 panels A and B beneath the disk 12, as shown in Fig. 4.

From the foregoing it should be obvious that a hemoglobinometer constructed in accordance with my invention, provides a device of relatively simple and compact form, and which may be made entirely of paper or cardboard. Further, the complete device is of card-like form so that a great number of them may be filed in a usual fiber or drawer box with the tabs 22 projecting upwardly and bearing the indicia identifying the person to whom the data on the face of the panel D relates.

A supply of these hemoglobinometers may be kept in a relatively small space, and when one is 75 to be used, it is removed, preferably with the sheet

27 inserted in the pocket as shown in Fig. 4. The person using it may then or later write on the inner face of the panel D the identifying data, remove the supply of strips 27 from the pocket, tear off one of the strips, secure a drop of blood, 5 and place it on the removed strip, and then insert the strip into the slot behind the disk 12 so that as the disk is rotated in the manner above specified, the areas 14 and openings 26 therein come into registry with the blood for ready and accurate comparison. After such test is made, the proper data may be entered on one of the lines on the inner face of the panel D, and the hemoglobinometer with the supply of strips therein placed in the proper file, according to the filing 15 system in use.

Furthermore, the hemoglobinometers embodying my invention are well adapted to be carried on the person, as in a pocket or case, so that they may be used at various places, and later filed 20 with the permanent record entered thereon.

I claim:

1. A hemoglobinometer comprising, a sheet of foldable material having thereon a plurality of panels folded one over the other in superimposed 25 relation to form an envelope-like substantially flat device, an indicating element rotatably attached to one of said panels and having thereon a plurality of areas of colors with openings provided in said element associated with said areas, 30 a marginal portion of said element projecting beyond one edge of said one panel, said sheet being constructed with an opening on the fold line between two of its panels, aligned with said projecting portion of the element and thru which 35 said portion of the element projects to facilitate rotation of said element, and another of said panels serving as a cover for said device and having thereon indicia on which recordings may be made. 40

2. A hemoglobinometer comprising, an elongated sheet of foldable material having thereon a plurality of creases dividing the sheet into a plurality of panels folded on said creases one over the other, an indicating element rotatably attached to one of said panels and having thereon a plurality of areas of colors, with openings provided in said element associated with said areas, 45 said one panel being folded against a second panel constructed with a sight opening thru which said areas of colors may be observed as said element rotates, and said sheet being constructed with an opening on the crease between said second panel and a third of said panels thru which an edge of said element projects to be engaged by 50 a finger to facilitate rotation of said element.

3. A hemoglobinometer comprising, an elongated sheet of foldable material having thereon a plurality of creases dividing the sheet into a plurality of panels folded on said creases one over the other, an indicating element rotatably attached to one of said panels and having thereon a plurality of areas of colors, with openings provided in said element associated with said areas, 60 said one panel being folded against a second panel constructed with a sight opening thru which said areas of colors may be observed as said element rotates, said sheet being constructed with an opening on the crease between said second panel and a third of said panels thru which an edge 65 of said element projects to be engaged by a finger to facilitate rotation of said element, and means to hold a slip of paper or the like, containing a specimen thereon beneath said element for direct comparison with the colored areas on said 70 75

element during rotation thereof past said sight opening.

4. A hemoglobinometer comprising, an elongated sheet of foldable material having thereon a plurality of creases dividing the sheet into a plurality of panels, an indicating element rotatably attached to one of said panels and having thereon a plurality of areas of colors, with openings provided in said element associated with said areas, 5 said one panel being folded against a second panel constructed with a sight opening thru which said area of colors may be observed as said element rotates, said sheet being constructed with an opening on the crease between said second panel and a third panel thru which an edge of said element projects to be engaged by a finger to effect rotation of said element, and means to hold a slip of paper or the like containing a specimen beneath said element for direct comparison 10 with the colored areas on said element during rotation thereof past said sight opening.
5. A hemoglobinometer comprising, an elongated sheet of foldable material having thereon a plurality of creases dividing the sheet into a plurality of panels, an indicating element rotatably attached to one of said panels and having thereon a plurality of areas of colors, with openings 15 provided in said element associated with said areas, said one panel being folded against a second panel constructed with a sight opening thru which said areas of colors may be observed as said element rotates, said sheet being constructed with an opening on the crease between said second panel and a third panel thru which an edge of said element projects to be engaged by a finger to effect rotation of said element, means to hold a slip of paper or the like containing a specimen beneath said element for direct comparison 20 with the colored areas on said element during rotation thereof past said sight opening.

ERWIN FRITZSCHING.
